(57) **CLAIM**

We claim the ornamental design for a base unit for a diffuser, as shown and described.

DESCRIPTION

FIG. 1 is a perspective view of a first embodiment of the base unit.

FIG. 2 is a front elevation view of the base unit of FIG. 1. FIG. 3 is a back elevation view of the base unit of FIG. 1. FIG. 4 is a left side elevation view of the base unit of FIG. 1.

FIG. 5 is a right side elevation view of the base unit of FIG. 1.

FIG. 6 is a top plan view of the base unit of FIG. 1.

FIG. 7 is a bottom plan view of the base unit of FIG. 1.

FIG. 8 is a perspective view of a second embodiment of the base unit.

FIG. 9 is a front elevation view of the base unit of FIG. 8.

FIG. 10 is a back elevation view of the base unit of FIG. 8.

FIG. 11 is a left side elevation view of the base unit of FIG. 8.

FIG. 12 is a right side elevation view of the base unit of FIG. 8.

FIG. 13 is a top plan view of the base unit of FIG. 8; and,

FIG. 14 is a bottom plan view of the base unit of FIG. 8.
